US00D771694S

(12) **United States Design Patent** (10) Patent No.: **US D771,694 S**
(45) Date of Patent: **** Nov. 15, 2016**

(54) **DISPLAY SCREEN OR PORTION THEREOF WITH ICON**

(71) Applicant: **Quantcast Corporation**, San Francisco, CA (US)

(72) Inventor: **Katherine Y. Long**, San Francisco, CA (US)

(73) Assignee: **Quantcast Corporation**, San Francisco, CA (US)

(**) Term: **15 Years**

(21) Appl. No.: **29/540,239**

(22) Filed: **Sep. 22, 2015**

(51) LOC (10) Cl. **14-04**

(52) U.S. Cl.

USPC **D14/488**; D14/492; D14/493

(58) **Field of Classification Search**

USPC D14/485-495; D15/8, 20, 59, 61, 65; D20/25, 31

CPC G06F 17/18; G06F 17/60

See application file for complete search history.

(57) **CLAIM**

The ornamental design for a display screen or portion thereof with icon, as shown and described.

DESCRIPTION

The FIGURE is a front view of a display screen or portion thereof with icon showing my new design.

The broken line showing of a portion of the display screen is for the purpose of illustrating environmental structure and forms no part of the claimed design.

1 Claim, 1 Drawing Sheet
